[57] CLAIM

The ornamental design for a garbage collection vehicle,
substantially as shown and described.

DESCRIPTION

FIG. 1 is a right side elevational view of a garbage collection vehicle showing our new design, the left side elevational view being a mirror image of that shown;
FIG. 2 is a top plan view thereof;
FIG. 3 is a bottom plan view thereof;
FIG. 4 is a rear elevational view thereof; and
FIG. 5 is a front elevational view thereof.
